PROCESS FOR MAKING CONTAINERS FROM
PAPER PULP AND APPARATUS THEREFOR

Raymond E. MacDonald, Westwood, Mass., assignor of one-half to Edwin M. Warwick, Walpole, Mass.

Application August 21, 1939, Serial No. 291,146

31 Claims. (Cl. 92—56)

This invention relates to a process for making a paper container with an integral bottom and side structure from paper slush or liquid pulp or the like, and apparatus therefor, and the product resulting therefrom.

My principal object is to make a container with an integral bottom and side structure of said liquid paper pulp that will have the necessary consistency and firmness required to permanently maintain its shape and which will be practical for commercial use. To accomplish this object I provide a new and novel process of manufacture, and new and novel apparatus to do the manufacturing.

Another object is to provide new devices for use in my apparatus such as an expanding member and a retainer receptacle, and which are capable of other uses than those described herein.

The foregoing and other objects which will appear as the nature of the invention is better understood, may be accomplished by a process of manufacture, and by apparatus of a construction, combination and operative arrangement of parts such as is disclosed by the drawings and specification. The nature of the invention is such as to render it susceptible to various changes and modifications, and, therefore, I am not to be limited to said disclosure; but am entitled to all such changes therefrom as fall within the scope of my claims.

In the drawings:

Figure 1 is a front elevational view of my apparatus with which a paper container is made from paper slush or liquid pulp, but without the retaining receptacle thereon and without the expanding device thereon, and Figure 2 is a plan sectional view taken on the line 2—2 of Figure 1, but on a slightly reduced scale.

Figure 3 is a longitudinal, sectional view of the screen former partly broken away, on which the container blank is first formed of said slush, and Figures 3a, 3b and 3c are plan views showing three baffles used in said former in disassembled position. Figure 4 is a plan view of said screen form and Figure 5 is a bottom view thereof.

Figure 6 is an end elevational view partly broken away, and partly in section, of a retainer receptacle adapted to receive and hold said container blank while it is being shaped and sized to its finished form. Figure 7 is a plan view of said retainer receptacle and Figure 8 is a bottom view of the shaft that rotates said retainer receptacle.

Figure 9 is a front elevational view, partly broken away, of one section of an upstanding

holder screen to which said blank is transferred, showing it disassembled from said retainer receptacle in which it is used, Figure 10 is a plan view and Figure 11 is a bottom view thereof.

Figure 12 is a fragmentary view, partly in section, and broken away, showing a portion of said retainer receptacle to illustrate the air ducts therein.

Figure 13 is a front elevational view, partly broken away, and partly in section, of the sleeve holder that holds said retainer receptacle during the shaping and sizing operations on said blank. Figure 14 is a plan view of said sleeve holder and Figure 15 is a bottom view thereof.

Figure 16 is a front elevational view, partly broken away, of a supporting base for the driving mechanism that rotates said retainer receptacle. Figure 17 is a plan view of said supporting base and Figure 18 is a bottom view thereof. Figure 19 is an enlarged, sectional, detail view of the slip joint shown broken away in the lower portion of Figure 16.

Figure 20 is a front elevational view, partly in section, of my expanding device which shapes and sizes said blank to its finished form. Figure 21 is a sectional view taken on the line 21—21 of Figure 20 and Figure 22 is a longitudinal sectional view showing the bottom housing for said expanding device separately.

Figure 23 is a plan view of the lower or upper horizontal supporting plate of the expander member, both being similarly constructed.

Figure 24 is a plan view of the lifting yoke used in my expanding member.

Figure 25 is a plan view of the tool holder that holds my expander member.

Figure 26 is a front elevational view of a hollow shaft connector that extends into said tool holder and that connects with the shaft that rotates the expander member rolls, Figure 27 is a plan view and Figure 28 is a bottom view thereof.

Figure 29 is a front elevational view, partly broken away and in section, showing a portion of the tool holder and the horizontal drive pulley above it, and the shaft connector that drives the expander member shaft.

Figure 30 is a plan sectional view of an upper portion of the expander member and the gears by means of which the expander member rolls are rotated.

Fig. 31 is a front elevation view, partly broken away and partly in section, of a finished, paper container fitted with a metal liner L.

As illustrated, my apparatus has a main frame 55 at one side of which is provided a separate ro-

tatable tank 26 to hold the paper slush or liquid pulp P that is preferably kept agitated, into which tank a former F extends and on the outside bottom and side wall of which said pulp P is sucked to first form the container blank B that is shown broken away on side former F in Figure 3 of the drawings. Said former F consists of a center rod 26 on which are mounted two intermediate baffle plates 29, a top baffle plate 30 and a bottom baffle plate 31, which baffle plates are spaced apart from each other and held to said center rod 26 by pins 32. Said baffle plates 29, 30 and 31 are provided with holes 33a, 33b and 33c respectively of different sizes as shown in the disassembled parts of Figure 3 of the drawings, the purpose of said holes being to control the exhaustion of the air from the interior of said former F so that said pulp P will be deposited evenly on the outside of said former at the bottom and side thereof. It will be noted that said holes 33b in said top baffle plate 30 are nearer the center and closer together than said holes 33a in the intermediate baffle plates 29, and that said holes 33c in the bottom baffle plate 31 are smaller and more numerous and spread throughout said plate 31, which also has an outside edge that is fluted as at 34 to provide further air passages. It will thus be seen that the air passages provided by said flutes 34 and holes 33a, 33b and 33c tend toward the center of said former F from bottom to top.

The outside of said former F consists of a piece of fine screening 35, such as 24 mesh, which has an integral bottom and side and terminates at the top in a loop 36 that extends downwardly a short distance, as shown in Figure 3 of the drawings, to thereby form a bead portion at the top edge of said container blank, which thicker top edge is especially desirable where said container is to have a screw-threaded cover. Bending wires 38 at the side enclose the parts of said former F, which also has a top member 39 held to said top baffle plate 30 by rivets 40, which top member 39 has a screw-threaded hole 41 adapted to receive a conduit 44 having a valve 45 and being connected to a vacuum tank 46 which preferably has sufficient capacity to create 12 pounds vacuum per square inch, and which has a drainage valve 47. Extending from said vacuum tank 46 is another conduit 48 which communicates with a compressor 49 of the usual type, extending from which is another conduit 50, which has a safety valve 51, and which conduit 50 connects to a pressure tank 52 having a pressure capacity of about 30 pounds, and which is provided with the usual pressure gauge 53. Said compressor 49 has a shaft 54 which extends outwardly and is provided with a pulley 55 on which is a moving belt 56 that extends to a motor pulley 57 that is rotated by an electric motor 58 of the usual type that is supplied with current coming through the usual cord or wire 59.

Another conduit 63 having a valve 65, extends from said pressure tank 52, and to this conduit is attached a flexible hose 64 through which air under about 30 pounds pressure passes to blow the container blank B off the screen former F, as will be later described.

Above said compressor 49 is a shelf 67 on which another electric motor 68 is mounted which is supplied with current passing through a wire 69 in the usual manner. Said motor 68 has a shaft 70 which is threaded to operatively connect with a worm 71 which in turn connects with a worm gear 72 which in turn is splined as at 74a, said

spline being fixed to a hollow shaft 74 whereby said shaft 74 is rotated. Said spline 74a and said shaft 74 slidably extend through holes 73 in center portions of a supporting structure 75. This sliding fit permits said shaft 74 and said spline 74a to be moved upwardly to thereby force said receptacle container upwardly sufficiently high to separate castings 133 and screen sections 146 associated therewith, later described, from the finished container R. Another flexible conduit 76, having a valve 77 communicates with said hollow shaft 74 through a slip joint J, so that a vacuum passage from said vacuum tank 46 through said hollow shaft 74 can be established. The lower end of said shaft 74 is fitted into and fixed to a hollow sleeve bearing 78 which has an opening in a boss portion 79 at the bottom to receive the end of a bearing pin 80. Said bearing 78 rotates with said shaft 74, and to establish a vacuum passage there are openings 81 provided in said sleeve bearing 78 as shown in Figure 19 through which water forced out of said container blank also passes to said vacuum tank 46.

There is another motor 86 mounted on said frame 25 that is supplied with current passing through a wire 87. It has a pulley 88 on its shaft on which a belt 89 runs between it and a horizontal pulley 90. A vertical shaft 91 is fixed to said pulley 90 and rotates therewith, being mounted in a bearing 92 forming part of a rectangular supporting base 93 for the upper structure of my apparatus. Mounted on splines 96 that are fixed to said shaft 91 is a loose pulley 95 which is adapted to move up and down on said splines 96. The upper end of said shaft 91 is rotatably mounted in a rectangular top member 98. A belt 97 extends from said pulley 95 to a larger drive pulley 99 fixed to a shaft connector 260 later described.

40 A connecting fork 101 is attached at its forked end to said pulley 95 and is attached to a strap 100 that is fixed at its opposite ends to two sliding collars 102 that slide on vertical rod 103 that is mounted in said supporting base 93 and said top member 98, being held in the latter by a nut 104. There are four said sliding collars 102 and four said rods 103. A tool holder 105 having four arms has two threaded sleeves 106 fixed therein and two boss portions 107 at the bottom to strengthen said holders 105. A central hole 108 extends through said tool holder 105 and is adapted to receive a connector shaft 260 later described. Outside of said hole 108 are threaded holes 109 which are adapted to receive bolts 109a that extend through holes 109 in a frame 250 and top 251 later described, whereby said expanding member 153 is removably connected to said tool holder 105. Two long screws 110 screw-threadedly engage said sleeves 106. Collars 111 hold said screws 110 in position. On each said screw 110 is a bevel gear 112 fixed thereto which meshes with another bevel gear 113 which is fixed to a hand wheel 115.

65 Immediately upon its formation the said moist container blank B while remaining on said former F is placed in a retainer receptacle 120 which fits into a sleeve holder 121 which is held firmly in place by a circular frame 122 having a bottom flange 123 in which holes 124 are formed through which bolts 125 extend and into a pedestal 126 that serves as a support for the above. Said container blank B is blown off said former F by a blast of air passing through said flexible hose 64 immediately after it is placed in said retainer

receptacle 120 and said former F is removed therefrom.

Connected to the lower portion or bottom 131 of said retainer receptacle 120 is a threaded, hollow, multiple fitting 130 which is held thereto by a sweat band 132, said fitting 130 connecting at its lower end to said hollow shaft 74. Said retainer receptacle lower portion 131 has an opening 130a of said multiple fitting 130 which has four branch openings 130b extending laterally therefrom. The main portion or body of said retainer receptacle 120 consists of four castings 133 that are strengthened by ribs 133a and 133b. Each said casting 133 has a central opening 136 which communicates with said multiple fitting branch openings 130b by means of four flexible conduits 134 each of which communicates with a said branch opening 130b. In each said castings 133 are two separate vertical air ducts 136a, which are in communication with said openings 136 and with vacuum chambers 138 formed in said castings 133. Each said casting 133 has a hinge portion 140 and there is a hole 141 that extends through said hinge portion 140 and through said retainer receptacle bottom 131 into which a pin 142 slidably fits. Each said casting 133 opens outwardly, thereby pulling away from the finished pulp container R after the retainer receptacle 120 is lifted upwardly in said sleeve holder 121, which may be done by forcing said hollow shaft 74 upwardly against it.

Said retainer receptacle lower portion 131 has upstanding teeth 143 that support a bottom screen 145 which provides a bottom for four said side screen sections 146 each of which is sweated to a said casting 133, so that each said side screen section 146 opens independently and outwardly together with a said casting 133 to thereby break the adhesion of said container blank B to said four side screen sections 146. In said castings 133 are lateral channels 148 which extend around the four said sections 133 and communicate with said air ducts 136a, which channels 148 provide space between said screen sections 146 and the outside of said castings 133 so that air withdrawn from said channels 148 creates a vacuum in the space surrounding the outside of said screen sections 146.

An expander member 155 enters the container blank B and while in the interior thereof it expands against the interior surface of said blank, and pressure rolls 158 force the material forming said blank outwardly until said blank B has a predetermined internal size. Said expander member 155 has a bottom housing 156 in one piece, three separate expanding rotatable rolls 158 that extend into and are movable in said bottom housing 156. Tie rods 159 extend into holes 160 in said bottom housing 156 and are driven into a horizontal supporting plate 183, later described, to thereby hold said bottom housing 156 in place. Locking pins 161 in holes 162 formed in said bottom housing 156 hold said tie rods 159 in place. Said rolls 158 rotate in the same direction as said retainer receptacle 120, and at the same surface speed of rotation, whereby a said roll 158 makes several complete revolutions in the same time said retainer receptacle 120 makes one revolution.

Formed in the lower portion of said bottom housing 156 is a recess 165 into which a wiper member 166 movably extends, being pivotally fastened by a pin 167 driven into said bottom housing 156 that permits an arcuate movement of said wiper member 166. Said wiper member 166

has a lip 168 and has a hole 169 extending through the body of said wiper 166 through which a stud shaft 172 fixed to the bottom of a said roll 158 passes and extends below into a recess 170 in said bottom housing 156 which is longer than said hole 169, as shown in Figure 22, to permit said stud shaft 172 at the bottom of a said roll 158 to move sidewise therein when said rolls 158 are moved outwardly in the expanding movement of said expander member 155. Only one said roll need have said wiper member 166 associated with it, which wiper remains in fixed position except that it makes an arcuate movement outwardly when the said roll 158 that it is associated with is moved laterally. The two other said rolls 158 have slightly shorter stud shafts 172 inasmuch as the said recesses 170 are not quite so far down in said bottom housing 156 because there are no wiper members 166 therein.

20 A central actuating rod 175 slidably fits into a hole 176 in said bottom housing 156. Near the lower end of said actuating rod 175 a cone member 177 is fastened thereto by a pin 178. Said cone member 177 rests on a seat 179 formed in said bottom housing 156. A wider portion of said cone member 177 normally extends below said rolls 158 and overhangs a portion of said rolls 158 as shown in Figure 20 of the drawings so that any upward movement of said actuating rod 175 helps to force said rolls 158 outwardly.

25 Said expander member 155 has a horizontal lower supporting plate 183 that is supported by said tie rods 159 as previously explained, and the tops of said rolls 158 terminate against the bottom of said supporting plate 183. There is also a horizontal upper plate 184 similar to said plate 183, supported by vertical columns 185 which are fastened to said lower and upper supporting plates 183 and 184 by screws 186 extending through holes 186a in said plates. Dowel pins 187 are driven into holes 188 in said plates 183 and 184 and extend into said columns 185, to prevent any lateral movement of said columns. Said supporting plates 183 and 184 each has a central hole 189 30 into which said actuating rod 175 slidably extends.

35 There are vertical journal members 190 that are adapted to be moved laterally which have bottom corner recesses 191 and have overhanging portions 192 directly above them as shown in Figure 20 of the drawings. In each said journal member 190 are three horizontal holes 193 extending into a boss 194 formed in said journal member 190 into which guide rods 195 extend and are fixed therein by pins 196. Said guide rods 195 40 slidably extend into and through holes 200 in said columns 185, which columns 185 have boss portions 201 in which said holes 200 terminate in counterbore holes 202 into which enter spiral springs 205 that extend around a portion of said rods 195 and bear against said journal member 190 at one end, and bear against an interior portion of said columns 185 at said counterbore holes 202 at the other end. Said springs 205 are compressed when said rolls 158 45 are forced outwardly, and when pressure on said rolls 158 is released said springs 205 automatically tend to return to normal position.

50 Two cone members 210 fixed on said actuating rod 175 and spaced apart have an upper, smaller portion that normally extends between said overhanging portions 192 as shown in Figure 20 of the drawings, so that any upward movement of said actuating rod 175 spreads said journal members 190 outwardly and inasmuch as each has a shaft 215 that revolves therein and is fixed in

said rolls 158 by pins 216 said rolls are also moved outwardly with the assistance of said lower cone member 171. Each said shaft 215 is fastened by a pin 218 to a rotatable, universal joint lower section 219 having a connecting link 220 that is attached to an upper section 221 to which a stud shaft 223 is fastened by a pin 224. Each said stud shaft 223 is fixed to a gear 225 and is driven thereby, which gears 225 each have a hub 226 through which a pin 227 extends to fasten said gears to said shafts 223.

Fixedly mounted on said actuating rod 175 is a lifting yoke 229 having a central boss portion 230 in which is a hole 231 through which said actuating rod 175 extends and is fixed thereto by a pin 228. Said yoke 229 has three arms 232 each having a boss extension portion 233 with a hole 234 therein through which a lifting rod 237 extends that is fixed to said boss portion 233 by a set screw 236 being fixedly held by a spring tension bushing 238 that is held in position by a set screw 239. Said lifting rods 237 slidably extend through holes 242 in said lower supporting plate 183. Extending around the top portion of said lifting rods 237 are spiral springs 243 which bear against said bushings 238 at one end, and bear against said upper supporting plate 184 at the other end, thus insuring the automatic return of said lifting rods 237 to normal position when pressure on them is relieved. Said plates 183 and 184 each have three longitudinal slots 245 similar to said recesses 170 previously described to permit lateral movement of said shafts 215 that carry said rolls 158.

Said lifting rods 237 normally extend a predetermined distance below said lower supporting plate 183 so that when said expander member 155 enters the container blank B and is some distance from the bottom thereof said rods 237 strike the top of said sleeve holder 121 thereby forcing said rods upwardly which in turn raise said lifting yoke 229 fixed to said rods 237 and which in turn raise said actuating rod 175 fixed to said yoke 229 thereby carrying said cone members 210 and 211 upwardly which force said rolls 158 laterally outward, said journal members 190 likewise moving laterally outward and compressing said springs 205. Said recesses 170 and slots 245 permit this laterally outward movement of said stud shafts 172 fixed on said rolls 158.

Said lifting rods 237 terminate at their upper ends at a point spaced from the bottom of said upper supporting plate 184 when in normal position, their exact location depending upon the position of said rods 237 in said boss extension portions 233. When it is desired to limit the lateral expansion of said rolls 158 said set screws 236 are loosened and said lifting rods 237 are pushed upwardly in said boss extension portions 233 to the point desired with the result that said lifting rods 237 do not contact the top of said sleeve holder 121 as soon during the downward movement of said expanding member, which in turn limits the lateral movement of said rolls 158 thereby determining the thickness of the wall of said container blank B. To increase the lateral expansion the opposite steps are taken.

The distance or extent that said expander member 155 enters said container blank B is determined by the distance between the bottom of said lower supporting plate 183 and the bottom surface of said bottom housing 156. When said lower supporting plate 183 contacts the top of said sleeve holder 121 the movement of said expander member 155 downwardly stops.

Said expander member 155 has an upper frame 250 that is held to said column 185 by said screws 186 and it has a top 251 held thereto by screws 253. A central solid drive shaft 255 rotatably extends through said top 251 and is fixed to an intermediate drive gear 257 that meshes with and drives said gears 225 as illustrated in Figure 30 of the drawings.

A shaft connector 260 consists of a round portion 261 having an opening 262 to receive said shaft 255, and has a rectangular portion 264, said round portion 261 extending through said tool holder central hole 108 while said rectangular portion 264 extends into said drive pulley 99 and is held rigidly therein by a set screw 265 so that said shaft connector 260 is rotated with said drive pulley 99. Said drive shaft 255 extends into said hole 262 and is held fixed therein by a set screw 267, and rotates with said shaft connector 260.

The process of making containers from liquid pulp or similar moist material and the operation of my apparatus is as follows:

The former F is inserted into said tank 26 which is rotated to insure more even distribution of said pulp on said former F, or said former could itself be rotated to accomplish this purpose. The motor 58 operates to exhaust said vacuum tank 46 by means of said compressor 49 that is in communication with said vacuum tank 46 and which is driven by said motor 58 through belt 56 as previously explained. The vacuum thus created upon opening said valve 45, sucks said liquid pulp around the outside of said former F at the side and bottom as previously explained, and the hollow container blank is formed thereon with integral bottom and side structures. Said former F is unscrewed from said conduit 44 and while the pulp container blank B is still soft and moist it is placed in said retainer receptacle 120 shown in Figure 6 of the drawings extending into said screen sections 146. Said valve 45 is closed and said valve 11 is opened to permit withdrawal of air from said retainer receptacle 120 which holds said container blank B in shape and firmly in position at its outside surface and prevents it from rotating independently of said retainer receptacle 120. Upon opening said valve 65 a blast of air passes through conduit 63 and through said flexible hose 64, and is directed into the interior of said former F to thereby force said container blank B off said former F whereupon said former F is withdrawn, leaving the blank B in said retainer receptacle 120. The force of the vacuum in the interior of said retainer receptacle and surrounding said blank B draws said blank onto said bottom screen 145 and said screen sections 146 all four of which are in said sleeve holder 121 and held together to thereby form a round screen container enclosing said blank B. This screen container is only slightly larger than said former F to permit the latter to slip fit therein. The blast of air is supplied from said pressure tank 52 and comes through said conduits 63 and 64 as will be clear from Figure 1 of the drawings.

While said blank B is firmly held at its outside surface on said screen sections 146 and bottom screen 145 by the force of vacuum which also draws water out of said moist blank container B into said vacuum tank 46, said expander member 155, which is removably fastened to said work holder 105 by bolts 109a, is moved downwardly and enters said container blank B by turning said hand wheel 115 which actuates said bevel gears 112 and 113 to thereby slide said work holder 105 carrying said expander member 155, down on

said screws 110. Said motor 86 now drives through intermediate power transmitting members the said pulley 99 which in turn rotates said shaft connector 260 and said expander member shaft 255 which in turn rotates the said three rolls 158 through said gear 257 and gears 225 and shafts 215. It is preferable to have said rolls 158 rotate as said expander member 155 enters said container blank B and also to have said retainer receptacle 120 rotate at the same time in the 10 same direction, the latter rotation being effected through the hollow shaft 74 which is rotated through gearing 71 and 72 operatively connected to said shaft 70 that is driven by said motor 68. Said retainer receptacle 120 should preferably 15 make a complete rotation in the same time said rolls 158 do. When said expander member has partly entered said container blank B said lifting rods 237 contact the top of said sleeve holder 121 in a manner previously described forcing said 20 rods 237 upwardly to whatever extent desired, causing said rolls 158 to move laterally against the interior wall structure of said container blank B a predetermined distance all depending upon how much the interior surface of said container blank B is to be compressed outwardly. For instance the wall or side of a blank container B when it is separated from said former F may be $10/32$ " thick, and after said expander member has entered and rolled its interior surface outwardly 25 it is compressed to a point where it is only $3/2$ " thick. The water that has been squeezed out of it passes through said air ducts or passages 148, 136a, 136, 134, 130b and hollow shaft 74, and also through openings 131a, 130a and 130b to said 30 hollow shaft 74 which communicates with said vacuum tank 46 as previously explained, from which tank it is finally withdrawn.

Said wiper member 166 is moved into contact with the lower interior surface of said container blank B in association with a said roll 158, thus providing an even, interior surface and ample thickness and toughness at this important arcuate portion U between the integral side structure and the flat bottom structure of said finished container R, as shown in Figure 31 of the drawings. The bottom of said expander member 155 presses down against the bottom of said container blank B to a predetermined extent that compresses the bottom of said container blank B more than the side, thus making said bottom thinner and more compact. The bottom may be only $2/32$ " thick as compared with a thickness of $3/2$ " of the side. Said arcuate portion U is likewise about $3/2$ " thick.

To lift the expander member out of the finished container R said hand wheel 115 is rotated which relieves the tension on said springs 243 and said springs 205 whereby the moving parts of said expander member return to normal position.

Said hollow shaft 74 is then pushed upwardly to force said retainer receptacle 120 partly out of said sleeve holder 121 sufficiently to permit said screen sections 146 and associated castings 133 to be opened outwardly on said hinge pins 142, which is done, to thereby separate them from the finished container R, which is taken out and dried, and may be fitted with a metal liner L of aluminum or the like or may be plated or treated with some substance or chemical composition if desired, to render it waterproof.

It is not necessary to have a slush or pulp tank 26 connected to my apparatus, as it can be dis-associated therewith inasmuch as my apparatus is principally concerned with the finishing or 75

processing of the container blank B after it has been formed on the former F.

What I claim is:

1. Apparatus for making containers from moist paper pulp, comprising a retainer receptacle adapted to hold a container blank made of said pulp, an expander member embodying a separate laterally moving expanding portion normally adjacent the outer surface of said member, means adapted to cause a portion of said expander to move downwardly into a said container blank while the latter is in said retainer receptacle, said expander member comprising movable means adapted upon actuation to move said laterally moving portion of said expander member laterally outward to thereby cause said portion to bear against the interior surface of said container blank when in said receptacle means cooperable with said movable means to effect actuation of the latter, and means to positively rotate said laterally moving portion.

2. Apparatus for making containers from moist paper pulp, comprising a rotatable retainer receptacle adapted to hold a container blank made of said pulp, means to rotate said receptacle about its axis, an expander member embodying a separate laterally moving portion, means adapted to cause a portion of said expander member to move downwardly into a said container blank while the latter is in said retainer receptacle, said expander member comprising movable means adapted upon actuation to move said laterally moving portion of said expander member laterally to thereby cause said portion to bear against the interior surface of said container blank, means cooperable with said movable means to effect actuation of the latter and means to rotate said expander member laterally moving portion.

3. Apparatus for making containers from moist paper pulp, comprising a rotatable retainer receptacle adapted to hold a container blank made of said pulp, supporting means therefor, means to rotate said receptacle about its axis, an expander member embodying separate roll means 40 adapted to rotate and to be moved horizontally outward to thereby enlarge said expander member, means adapted to cause a portion of said expander member and roll means to move into a said container blank while the latter is in said retainer receptacle, said expander member comprising movable means adapted upon actuation to move said roll means horizontally outward to thereby cause said roll means to bear against the interior surface of said container blank, means 45 cooperable with said movable means to effect actuation of the latter and means to rotate said roll means.

4. Apparatus for making containers from moist paper pulp, comprising a rotatable retainer receptacle adapted to hold a container blank made of said pulp, means to rotate said receptacle about its axis, an expander member embodying a plurality of rolls adapted to be moved laterally and to rotate, means adapted to cause a portion 60 of said expander member and rolls to move into a said container blank while the latter is in said retainer receptacle, said expander member comprising movable means adapted upon actuation to move said rolls laterally to thereby cause said rolls to bear against the interior surface of said container blank, means cooperable with said movable means to effect actuation of the latter and positive driving means to rotate said rolls.

5. Apparatus for making containers from moist paper pulp, comprising a retainer receptacle

adapted to hold a container blank of said pulp, an expander member embodying a laterally movable portion, and a wiper member at its lower portion in operable association with said portion, means adapted to cause a portion of said expander member to move into a said container blank while the latter is in said retainer receptacle, said expander member comprising movable means adapted upon actuation to move said laterally moving portion of said expander member and said wiper member laterally to thereby cause said portion to press against the interior surface of said container blank, and means cooperable with said movable means to effect actuation of the latter.

6. Apparatus for making containers from moist paper pulp, comprising a retainer receptacle adapted to hold a container blank of said pulp, an expander member embodying laterally movable and rotatable rolls, a wiper member at the lower portion thereof means operably connecting said wiper member with one of said rolls to cause lateral movement of said wiper member with said roll, means adapted to cause a portion of said expander member to move into a said container blank while the latter is in said retainer receptacle, said expander member comprising movable means adapted upon actuation to move said laterally moving rolls and said wiper laterally to thereby cause said rolls and wiper member to press against the interior surface of said container blank, means cooperable with said movable means to effect actuation of the latter and means to rotate said rolls.

7. Apparatus for making containers from moist paper pulp, comprising a retainer receptacle adapted to hold a container blank of said pulp, an expander member embodying laterally movable and rotatable rolls, a wiper member at the lower portion thereof and in operable association with one of said rolls during lateral movement thereof, means adapted to cause a portion of said expander member to move into a said container blank while the latter is in said retainer receptacle, said expander member comprising movable means adapted upon actuation to move said laterally moving rolls and said wiper laterally to thereby cause said rolls and wiper member to press against the interior surface of said container blank, means cooperable with said movable means to effect actuation of the latter and means to rotate said rolls and means to hold said wiper from rotating while said roll it is associated with is rotating.

8. Apparatus for making containers from moist paper pulp, comprising a retainer receptacle adapted to hold a container blank of said pulp, means embodying a conduit in communication with said receptacle and a source of suction whereby sufficient force is created on the outside surface of said container blank while in said receptacle to hold its external shape and hold it in position while pressure is applied on its interior surface, an expander member embodying a separate movable upright roll, means adapted to cause a portion of said expander member and said roll to move into a said container blank while the latter is in said retainer receptacle, said expander member comprising movable means adapted upon actuation to move said laterally moving roll of said expander member laterally while retaining its upright position to thereby cause said portion to press against the interior surface of said container blank, and means co-

operable with said movable means to effect actuation of the latter.

9. Apparatus for making containers from moist paper pulp, comprising a retainer receptacle adapted to hold a container blank of said pulp, and having air space between its outside surface and the portion adapted to receive said container blank, means adapted to hold said container blank in position while pressure is applied on its interior surface, an expander member embodying a plurality of laterally movable and vertically extending members at its outer portion, means above said laterally moving members adapted to cause a portion of said expander member and said movable members to move into a said container blank while the latter is in said retainer receptacle, said expander member embodying movable means above said laterally moving members adapted upon actuation to move said laterally moving members outwardly to thereby cause said members to press against the interior surface of a said container blank, and means cooperable with said movable means to effect actuation of the latter.

10. Apparatus for making containers from moist paper pulp, comprising a retainer receptacle adapted to hold a container blank of said pulp, means adapted to hold said container blank in fixed position in said receptacle while pressure is applied on its interior surface, an expander member embodying three laterally movable rolls, means adapted to cause a portion of said expander member to move into a said container blank while the latter is in said retainer receptacle, said expander member comprising movable means adapted upon actuation to move said three rolls outward laterally to thereby cause said portion to press against the interior surface of a said container blank, and means cooperable with said movable means to effect actuation of the latter.

11. Apparatus for making containers from moist paper pulp, comprising a retainer receptacle adapted to hold a container blank of said pulp, said receptacle embodying a screen portion and an outer member associated with and having portions spaced from said screen portion to thereby provide air space between said screen portion and said member, and having a passage for the escape of air in communication with said air space, means to withdraw air from said air space and out of said passage, an expander member embodying laterally movable and rotatable means and means to cause rotation thereof, movable instrumentalities adapted upon actuation to cause said laterally movable means to move laterally to thereby press said laterally movable means against the interior surface of said container blank, means cooperable with said movable instrumentalities to effect actuation of the latter, and means to move a portion of said expander member vertically into and out of a said container blank while the latter is in said retainer receptacle.

12. Apparatus for making containers from moist paper pulp, comprising a retainer receptacle adapted to hold a container blank of said pulp, said receptacle embodying a plurality of screen sections and outer members in association therewith having portions spaced from said screen sections to thereby provide air space between said screen sections and said outer members and having a passage for the escape of air in communication with said air space, means to withdraw air from said air space and out of said passage,

an expander member embodying laterally movable and rotatable means, means to cause rotation of said last mentioned means, movable instrumentalities adapted upon actuation to cause said laterally movable means to move laterally to thereby press said laterally movable means against the interior surface of said container blank, means cooperable with said movable instrumentalities to effect actuation of the latter, means to move a portion of said expander member vertically into and out of a said container blank while the latter is in said retainer receptacle, and means to rotate said retainer receptacle embodying a hollow rotatable shaft in communication with said passage.

13. Apparatus for making containers from moist paper pulp, comprising a retainer receptacle adapted to hold a container blank of said pulp, a hollow sleeve adapted to receive said receptacle, an expander member embodying laterally movable and rotatable means and mechanism adapted to cause positive rotation thereof, movable instrumentalities adapted upon actuation to cooperate with said hollow sleeve to cause said laterally movable means to move laterally to thereby press said laterally movable means against the interior surface of said container blank, and means to move a portion of said expander member vertically into and out of a said container blank while a said blank is in said retainer receptacle.

14. Apparatus for making containers from moist paper pulp, comprising a retainer receptacle adapted to hold a container blank of said pulp, supporting means, a hollow sleeve supported on end on said supporting means and adapted to receive said retainer receptacle, an expander member adapted to enter said receptacle embodying laterally movable and rotatable means and means to cause rotation thereof, movable instrumentalities adapted upon actuation to cause said laterally movable means to move laterally, said instrumentalities embodying lifting rod means so positioned with relation to said hollow sleeve that downward movement of said expander member brings said lifting rod means into contact with said hollow sleeve to thereby force said rod means upwardly and actuate said instrumentalities to cause lateral movement of said laterally movable means.

15. Apparatus for making containers from moist paper pulp, comprising a retainer receptacle adapted to hold a container blank of said pulp, supporting means, a hollow sleeve supported on end on said supporting means and adapted to receive said retainer receptacle, an expander member adapted to enter said receptacle embodying laterally movable and rotatable means and means to cause rotation thereof, movable instrumentalities adapted upon actuation to cause said laterally movable means to move laterally, said instrumentalities embodying a plurality of lifting rods positioned directly above a top portion of said hollow sleeve so that downward movement of said expander member brings said lifting rods into contact with said hollow sleeve top portion to thereby force said rods upwardly and actuate said instrumentalities to cause lateral movement of said laterally movable means.

16. Apparatus for making containers from moist paper pulp, comprising a retainer receptacle adapted to hold a container blank of said pulp, supporting means, a hollow sleeve supported on end on said supporting means and adapted to receive said retainer receptacle, an

expander member adapted to enter said receptacle embodying laterally movable and rotatable means and means to cause rotation thereof, vertically and horizontally movable instrumentalities adapted upon actuation to cause said laterally movable means to move laterally, said instrumentalities embodying vertically moving lifting rod means so positioned with relation to said hollow sleeve that downward movement of said expander member brings said lifting rod means into contact with said hollow sleeve to thereby force said rod means upwardly and actuate some of said instrumentalities horizontally to cause lateral movement of said laterally movable means.

17. Apparatus for making containers from moist paper pulp, comprising a retainer receptacle adapted to hold a container blank of said pulp, supporting means, a hollow sleeve supported on end on said supporting means and adapted to receive said retainer receptacle, said receptacle embodying a screen portion and an outer member associated with and having portions spaced from said screen portion to thereby provide air space between said screen portion and said outer member and having a passage for the escape of air in communication with said air space, instrumentalities to rotate said retainer receptacle embodying a hollow shaft in communication with said space, an expander member adapted to be moved into said retainer receptacle embodying a plurality of movable rolls spaced apart, vertically and horizontally movable instrumentalities adapted upon actuation to cause said laterally movable rolls to move laterally beyond the remainder of said expander member, said instrumentalities embodying upwardly moving lifting rods so positioned with relation to said hollow sleeve that downward movement of said expander member brings said lifting rods into contact with said hollow sleeve to thereby force said lifting rods upwardly and actuate some of said instrumentalities horizontally to thereby cause lateral movement of said rolls.

18. Apparatus for making containers from moist paper pulp, comprising a retainer receptacle adapted to hold a container blank of said pulp, supporting means, a hollow sleeve supported on end on said supporting means and adapted to receive said retainer receptacle, said receptacle embodying a screen portion and an outer member associated with and having portions spaced from said screen portion to thereby provide air space between said screen portion and said outer member and having a passage for the escape of air in communication with said air space, instrumentalities to rotate said retainer receptacle embodying a hollow shaft in communication with said space, an expander member adapted to be moved into said retainer receptacle embodying a plurality of movable rolls spaced apart, vertically and horizontally movable instrumentalities adapted upon actuation to cause said laterally movable rolls to move laterally beyond the remainder of said expander member, said instrumentalities embodying vertically moving lifting rods so positioned with relation to said hollow sleeve that downward movement of said expander member brings said lifting rods into contact with said hollow sleeve to thereby force said lifting rods upwardly and actuate some of said instrumentalities horizontally to thereby cause lateral movement of said rolls.

19. Apparatus for making containers from moist paper pulp, comprising a retainer receptacle embodying laterally movable and rotatable means and means to cause rotation thereof, vertically and horizontally movable instrumentalities adapted upon actuation to cause said laterally movable means to move laterally, said instrumentalities embodying vertically moving lifting rod means so positioned with relation to said hollow sleeve that downward movement of said expander member brings said lifting rod means into contact with said hollow sleeve to thereby force said rod means upwardly and actuate some of said instrumentalities horizontally to thereby cause lateral movement of said rolls, and means to hold said rolls in vertical position at all times.

20. Apparatus for making containers from moist paper pulp, comprising a retainer receptacle

cle adapted to hold a container blank of said pulp, supporting means, a hollow sleeve supported on end on said supporting means and adapted to receive said retainer receptacle, said receptacle embodying a screen portion and an outer member associated with and having portions spaced from said screen portion to thereby provide air space between said screen portion and said outer member and having a passage for the escape of air in communicating with said air space, instrumentalities to rotate said retainer receptacle embodying a hollow shaft in communication with said space, an expander member adapted to be moved into said retainer receptacle embodying a plurality of movable rolls spaced apart, vertically and horizontally movable instrumentalities adapted upon actuation to cause said laterally movable rolls to move laterally beyond the remainder of said expander member, said instrumentalities embodying an actuating rod carrying cone means, upwardly moving lifting rods operably associated with said actuating rod and so positioned with relation to said hollow sleeve that downward movement of said expander member brings said lifting rods into contact with said hollow sleeve to thereby force said lifting rods upwardly and actuate said cone means and thereby actuate some of said instrumentalities horizontally to thereby cause lateral movement of said rods.

20. Apparatus for making containers from moist paper pulp, comprising a retainer receptacle adapted to hold a container blank of said pulp, supporting means, a hollow sleeve supported on end on said supporting means and adapted to receive said retainer receptacle, said receptacle embodying a screen portion and an outer member associated with and having portions spaced from said screen portion to thereby provide air space between said screen portion and said outer member and having a passage for the escape of air in communication with said air space, instrumentalities to rotate said retainer receptacle embodying a hollow shaft in communication with said space, an expander member adapted to be moved into said retainer receptacle embodying a plurality of movable rolls spaced apart, vertically and horizontally movable instrumentalities adapted upon actuation to cause said laterally movable rolls to move laterally, said instrumentalities embodying journal members spaced apart laterally and adapted to move horizontally, an actuating rod carrying a cone member adapted upon actuation of said rod to enter said space between said journal members and force said journal members horizontally outward and vertically moving lifting rods operably associated with said actuating rod and so positioned with relation to said hollow sleeve that downward movement of said expander member bring said lifting rods into contact with said hollow sleeve to thereby force said lifting rods upwardly and actuate said actuating rod and said cone members to thereby move said journal members horizontally to thereby cause lateral movement of said rolls.

21. Apparatus for making containers from moist paper pulp, comprising means to create a suction, supporting means, means adapted to receive a container blank supported by said supporting means and having openings therein, instrumentalities to rotate said retainer receptacle embodying a hollow shaft in communication with said suction means and said openings, means adapted to smooth the interior of a said container embodying a separately movable portion

5 an outside surface of which is adapted to be moved horizontally and to enter said retainer receptacle and to be rotated therein, means adapted upon actuation to move said smoothing means upwardly and downwardly, means to move said outside surface horizontally, means cooperable with said movable means to effect actuation of the latter, and positive driving means operably connected to and adapted upon actuation to rotate said portion.

10 22. Apparatus for making containers from moist paper pulp, comprising means to create a suction supporting means, means adapted to hold a container blank supported by said supporting means and having openings therein in the interior thereof and having channels in an exterior portion in communication with said openings, instrumentalities to rotate said retainer receptacle embodying a hollow shaft in communication with said suction means and said openings, an expander member embodying a portion adapted to enter said retainer receptacle having a plurality of rotatable rolls that are adapted to move outwardly, movable means adapted to move them outwardly, means cooperable with said movable means to effect actuation of the latter, means adapted upon actuation to move said expander member upwardly and downwardly, and driving means operably connected to and adapted upon actuation to rotate said expander member portion and positive driving means to independently rotate said rolls.

15 23. Apparatus for making containers from moist paper pulp, comprising means to create a suction, supporting means, means adapted to hold a container blank supported by said supporting means and having openings therein, instrumentalities to rotate said retainer receptacle embodying a hollow shaft in communication with said suction means and said openings, a movable tool holder, an expander member embodying a portion adapted to enter said retainer receptacle and having portions adapted to be moved horizontally outward and to be rotated, instrumentalities operatively connecting said tool holder to said expander member, movable means adapted to move said portions outwardly, means cooperable with said movable means to effect actuation of the latter, means adapted upon actuation to move said tool holder and expander member upwardly and downwardly, and positive driving means operably connected to and adapted upon actuation to rotate said expander member rotatable portions.

20 24. Apparatus for making containers from moist paper pulp, comprising means adapted to hold a container blank, an expander member embodying a plurality of vertically extending rolls that are adapted to be moved laterally and to rotate and embodying a housing that forms the bottom of said member and a wiper member connected to one of said rolls and adapted to be moved laterally therewith, instrumentalities adapted to rotate said expander member and said rolls, and instrumentalities adapted upon actuation to move said rolls laterally outward, and means cooperative with said latter instrumentalities to effect actuation of the latter.

25 25. Apparatus for making containers from moist paper pulp, comprising means adapted to hold a container blank, an expander member embodying a plurality of rolls that are adapted to be moved laterally and to rotate and embodying a housing that forms the bottom of said member and a wiper member connected to one of said

rolls and adapted to be moved laterally therewith, instrumentalities adapted to rotate said expander member and said rolls, and instrumentalities adapted upon actuation to move said rolls laterally outward, means cooperative with said latter instrumentalities to effect actuation of the latter, said housing member having a recess therein to receive a portion of said wiper member.

26. A process in making a paper container from a moist paper pulp pre-formed container blank comprising placing said blank in a retainer receptacle and while it is still moist, rotating a member against the interior of the side wall of said blank and simultaneously rotating said retainer receptacle.

27. A process in making a paper container from a moist paper pulp pre-formed container blank comprising holding said blank in a retainer receptacle and while it is still moist in a fixed position, rotating a member against the interior of the side wall of said blank and simultaneously rotating said retainer receptacle.

28. A process in making a paper container from a moist paper pulp pre-formed container blank comprising holding said blank in a fixed position in a retainer receptacle and while it is still moist, rotating a portion of an expanding member against the interior of the side wall of said blank and simultaneously rotating said retainer receptacle.

5 tacle while holding said blank in said fixed position in said receptacle.

29. A process in making a paper container from a moist paper pulp pre-formed container blank comprising holding said blank in a retainer receptacle in a fixed position, and while it is still moist rotating a portion of an expanding member against the interior of the side wall of said blank and simultaneously rotating said retainer receptacle in the same direction as said portion.

10 15 30. A process in making a paper container from a moist paper pulp pre-formed container blank comprising holding said blank in a retainer receptacle in a fixed position, and while it is still moist rotating portions of an expanding member against the interior of the side wall of said blank and simultaneously rotating said retainer receptacle in the same direction as said portions at the same surface speed.

25 31. A process in the making a paper container from a moist paper pulp pre-formed container blank comprising placing said blank in a retainer receptacle and while it is still moist, rotating spaced-apart portions of an expanding member against interior portions of the side wall of said blank at points some of which are spaced apart at least 45 degrees from each other, and simultaneously rotating said retainer receptacle.

RAYMOND E. MACDONALD.
